[57] CLAIM

The ornamental design for a pull-on garment, as shown and described.

DESCRIPTION

FIG. 1 is a perspective view of a pull-on garment embodying our new design;

FIG. 2 is a front side elevational view thereof;

FIG. 3 is a rear side elevational view thereof;

FIG. 4 is a top plan view thereof;

FIG. 5 is a bottom plan view thereof;

FIG. 6 is a right side elevational view thereof; and,

FIG. 7 is a front side elevational view in use, the broken line showing being for illustrative purposes only and forming no part of the claimed design.
